UNITED STATES PATENT OFFICE

108,001

DESIGN FOR A MOTOR DRIVEN PORTABLE COMPRESSOR

Joseph W. Jones, Corning, N. Y., assignor to
Ingersoll-Rand Company, Jersey City, N. J.,
a corporation of New Jersey

Application November 17, 1937, Serial No. 72,949

Term of patent 14 years

To all whom it may concern:

Be it known that I, Joseph W. Jones, a citizen
of the United States, residing at No. 52 East 5th
Street, Corning, in the county of Steuben and
State of New York, have invented a new, original,
and ornamental Design for a Motor Driven Port-
able Compressor, of which the following is a
specification, reference being had to the accom-
panying drawing, forming part thereof.

In the drawing Fig. 1 is a side view of a motor

driven portable compressor showing my new de-
sign.

Fig. 2 is a rear elevation of the same design of
portable compressor.

Fig. 3 is a front elevation of the same design.

I claim:

The ornamental design for a motor driven
portable compressor, as shown.

JOSEPH W. JONES.
